US0D1086888S

(12) **United States Design Patent** (10) **Patent No.:** **US D1,086,888 S**
(45) **Date of Patent:** **** Aug. 5, 2025**

(54) **LAUNDRY TREATMENT PACKET**

(71) Applicant: **Tufco, L.P.**, Los Angeles, CA (US)

(72) Inventor: **Egal Gabbay**, Los Angeles, CA (US)

(73) Assignee: **Tufco, L.P.**, Los Angeles, CA (US)

(**) Term: **15 Years**

(21) Appl. No.: **29/919,326**

(22) Filed: **Dec. 4, 2023**

(51) **LOC (15) Cl. 09-05**

(52) **U.S. Cl.**

USPC **D9/707; D28/8.1**

(58) **Field of Classification Search**

USPC D28/4, 5, 6, 8.1, 8.2; D9/426, 707, 710,
D9/732

CPC . C11D 17/00; C11D 17/0047; C11D 17/0086;
C11D 17/0091; C11D 17/0095

(57) **CLAIM**

The ornamental design for a laundry treatment packet, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top front right view of a laundry treatment packet;

FIG. 2 is a back view thereof;

FIG. 3 is a front view thereof;

FIG. 4 is a left-side view thereof;

FIG. 5 is a right-side view thereof;

FIG. 6 is a top view thereof; and,

FIG. 7 is a bottom view thereof.

The broken lines shown represent unclaimed subject matter and form no part of the claimed design.

1 Claim, 5 Drawing Sheets
